UNITED STATES PATENT OFFICE.

MILLER COOK, JR., OF WHITMAN, MASSACHUSETTS, ASSIGNOR, BY DIRECT AND MESNE ASSIGNMENTS, TO BOSTON MACHINE WORKS COMPANY, OF LYNN, MASSACHUSETTS, A CORPORATION OF MASSACHUSETTS.

SOLE CUTTING AND MARKING MACHINE.

957,598.

Specification of Letters Patent. Patented May 10, 1910.

Application filed March 8, 1906. Serial No. 304,866.

To all whom it may concern:

Be it known that I, MILLER COOK, JR., of Whitman, in the county of Plymouth and State of Massachusetts, have invented certain new and useful Improvements in Sole Cutting and Marking Machines, of which the following is a specification.

This invention consists in a machine for cutting into soles which have been channeled or are to be channeled, at their opposite edges where the lips of the channels are formed. It is particularly adapted for acting upon inner soles to be used in welted shoes, and when used with this class of work is designed to cut off the channel lips at the points where the welt is adapted to terminate, on opposite sides of the shoe. This point is approximately on the line where the shank portion merges into the heel portion of the sole, and is slightly in rear of the line occupied by the breast of the heel which is later applied. The machine is also adapted to indent and mark the sole directly across the same between the cuts made in the channel lips, so as to provide a mark which will guide the operator in trimming off the welt.

In the drawings accompanying this specification, there is shown a machine representing one embodiment of my invention.

Of the drawings,—Figure 1 represents a plan view of the machine. Fig. 2 represents a side elevation thereof. Fig. 3 represents a front elevation. Fig. 4 represents a plan view of the forward base portion of the machine and a sole in place. Fig. 5 represents an under plan view. Fig. 6 represents a longitudinal central section. Fig. 7 represents a longitudinal section on line 7—7 of Fig. 1. Figs. 8 and 9 represent similar perspective views of a sole after the same has been acted upon by the machine, and before and after the lip of the channel has been turned up.

The same reference characters indicate the same parts in all the figures.

The machine comprises a base 1 having a flat upper surface 2 which serves as a table or support for a sole 3 which is to be acted upon.

On the sides of the base are formed ears 4 between which are contained depending ears 5 of a frame 6 which constitutes an oscillating or vibrating cutter-head. The ears 4 and 5 are provided with alined bores through

which are passed pintles 7, which are detachable and are held in place by screws 8 passing through them into the top 2 of the base.

The forward part of the frame consists of a transverse bar 9 which serves as a support and guide for two cutting tool holders 10. These holders are substantially L-shaped, each having an upright portion 11 extending beside the forward side of the cross bar 9 and an approximately horizontal portion 12 extending toward the rear of the machine and pivoted to the frame or head by means of screw-studs 13 passing through a rear cross bar 14. The upright arms 11 of the tool holders are sustained by means of plates 15^a fastened to them by means of screws 16^a, said plates projecting over the upper surface of the bar 9.

Each of the tool holders 10 carries a cutting tool represented as a knife 15 secured to the holder by a clamp 16 on the forward side thereof. A thumb screw 17 passes through the plate 15^a of each holder and bears against the blade, acting as a stop against which the blade abuts. As the screw is adjustable, it may be turned so as to cause greater or less penetration of the knife into the work, and when once adjusted, the knife is held in place by tightening up the screws of the clamp 16.

Between the cutting tool holders is an indenting tool 18 held to the forward bar 9 of the frame by means of screws 19 passing through slots 20 in the tool, whereby the latter may be adjusted vertically. A stop screw 21 passing through a plate 22 secured by a screw 23 to the bar 9 and projecting forward over the indenting tool, serves as an adjustable abutment for the indenting tool. The cutting edges of the knives and the marking edge of the indenting tool are all approximately in alinement and are adapted when moved into engagement with a sole, to make two separated cuts adjacent the opposite edges of the sole, and a line of indentations on the upper surface of the sole joining the cuts.

The frame or head is oscillated by means of a shaft 24 carrying an eccentric 25 around which extends an eccentric strap 26 having a rod 27 pivoted at 28 to a rear slotted extension 29 of the tool-carrying head. The oscillation of the head produced by rotation of the shaft causes the knives

and marking tool to be alternately moved toward and from the supporting plate 2 and a sole supported thereon, to cut and mark the upper surface thereof. The amounts by which the knives penetrate the sole and the depths of the indentations made by tool 18 are regulated by the positions of the stop screws 17 and 21 so that these incisions and indentations may be made as deep as desired. 5 Figs. 8 and 9 show insoles which have been acted upon by the machine to cut transversely through the channel lips at the points where the welt is to terminate. The knives make incisions *a* *b* deep enough to 10 cut through the flap *c* of the channel so that when the latter is turned up, as in Fig. 9, the heel end thereof will be square. The indenting tool makes a mark *d* extending 15 between and in line with the incisions and serving as a guide for the workman, by 20 which to trim off the ends of the welt even with the ends of the channel flap after the welt has been sewed on. This is to make 25 sure that the ends of the welt shall not extend too far toward the heel or be trimmed off too short, for after the upper and welt have been sewed to the rib formed by the channel flap, the latter is somewhat obscured and it is not easy for the workman 30 to see the end thereof.

For positioning the sole with respect to the tools, I provide a rear gage 30 against which the heel end of the sole is adapted to bear, and side gages 31 32. These side 35 gages are mounted upon arms 33 34 pivoted to the under side of the base, and are connected together by means of a pivoted lever 35 and links 36 37. A spring 38 is connected to the base and to lever 35, tending 40 to move the side gages 32 yieldingly together. These three gages embrace between them the heel portion of a sole and position the latter accurately with respect to the knives. The side gages are automatically 45 adjustable through the spring to fit soles of all widths, while the end gage 30 is manually adjustable longitudinally for soles of different lengths. To this end it is connected to a block 39 mounted in a guideway 50 in the support 2, and has upon its under surface a rack 40 with which meshes a pinion 41 on a shaft 42. The shaft extends to the side of the machine and has upon it an arm 43 which may be shifted to turn the 55 shaft and so move the gage. This arm has a pointer 44 adjacent a segment 45 which may be graduated for sizes of shoes, so that the end gage may be placed to position the sole for a cut at exactly the right point, 60 according to the size of the shoe for which the sole is to be used.

In order to make the cuts at the edges of soles having different widths as well as to determine the amount by which the cuts 65 extend inward from the edges, the knife

holders and knives are made laterally adjustable about the pivots 13 of the holders, and means are provided for adjusting them simultaneously and equally. This means consists of a cam 46 connected to a rod 47 mounted in a bracket 48 fastened to and extending from the front bar 9 of the head. The cam has two eccentric slots 49 into each of which extends a stud 50 mounted upon the horizontal arm of each tool holder. An arm 51 having a handle and a pointer is connected to the shaft 47, whereby to turn the cam. When the arm is shifted, the tool holders are moved inwardly or outwardly at the same time and by equal amounts. 70

The machine above described is one which performs an operation which has hitherto always been done by hand, and accordingly constitutes an entirely new departure. It has provisions for accurately adjusting the 85 sole so that the cuts will be made at exactly the right point, and for adjusting the knives so that the amount of penetration will be exactly right and the lateral extent of the cuts will also be correct. These results have 90 been impossible or difficult of attainment under the old method of cutting the channel lips by hand, and accordingly a great improvement in the art has been made by enabling this operation to be performed with 95 much greater rapidity and accuracy than hitherto, and with absolutely no danger of injuring the soles. 80

I claim:—

1. A sole-cutting machine comprising provisions for supporting and positioning the heel portion of a sole, and cutting means arranged for making separated incisions in the upper surface of the sole adjacent the edges thereof, leaving the surface between the incisions intact. 100

2. A sole-cutting and marking machine comprising provisions for supporting and positioning the heel portion of a sole, cutting means arranged for making incisions in the upper surface of the sole adjacent the edges thereof, and a marking device for indenting the sole between said incisions. 110

3. A sole-cutting machine comprising means for supporting and positioning a channelled sole, and cutting means arranged to cut the lips of the channels adjacent the heel portion of the sole. 115

4. A sole-cutting and marking machine comprising means for supporting and positioning a channelled sole, cutting means arranged to cut the lips of the channels adjacent the heel portion of the sole, and a non-penetrating indenting stop arranged between said cutting means to limit the penetration thereof and produce an indented mark between the incisions made thereby. 120

5. A sole-cutting machine comprising means for supporting and positioning a channelled sole, and cutting means arranged 125

- to cut the lips of the channels adjacent the heel portion of the sole, said cutting means being adjustable to vary the depth of cut. 5
6. A sole-cutting machine comprising a support for a sole, separated cutters adapted to make independent separated incisions in the surface of said sole adjacent its opposite edges, and a gage for positioning said sole with respect to the cutters. 10
7. A sole-cutting machine comprising a support for a channeled sole, independent cutters adapted to independently sever the lips of the channels transversely adjacent the heel end of the sole, and gages for positioning the sole with respect to the cutters. 15
8. A sole-cutting machine comprising a support for a channeled sole, independent cutters adapted to independently sever the lips of the channels transversely adjacent the heel end of the sole, and gages adjustable for different sizes of soles for positioning the sole with respect to the cutters. 20
9. A sole-cutting machine comprising a support for a channeled sole, cutters adapted to sever the lips of the channels transversely adjacent the heel end of the sole, and end and side gages for positioning the sole with respect to the cutters. 25
10. A sole-cutting machine comprising a support for a channeled sole, cutters adapted to sever the lips of the channels transversely adjacent the heel end of the sole, end and side gages for positioning the sole with respect to the cutters, and means for adjusting the gages for different sizes and widths of soles. 30
11. A sole-cutting machine comprising a support for a channeled sole, cutters adapted to sever the lips of the channels transversely adjacent the heel end of the sole, end and side gages for positioning the sole with respect to the cutters, and independent means for separately adjusting the gages for different sizes and widths of soles. 35
12. A sole-cutting machine comprising a support for a channeled sole, cutters adapted to sever the lips of the channels transversely adjacent the heel end of the sole, an end gage movable longitudinally of the sole, side gages laterally movable, and means to adjust said gages for different sizes and shapes of soles to position the latter with respect to the cutters. 40
13. A sole-cutting machine comprising a support for a sole, separated cutters having knife edges in alinement movable perpendicularly toward the support, and provisions for positioning a sole with its length transverse to the line of the knife edges and the dividing line of the forward end of its heel and rear end of its shank portion adjacent thereto. 45
14. A sole-cutting and marking machine comprising a support for a sole, separated cutters having knife edges in alinement, provisions for positioning a sole with its length transverse to the line of the knife edges and the dividing line of the forward end of its heel and rear end of its shank portion adjacent thereto, and provisions for positioning a sole with its length transverse to the line of the knife edges and its edges at the merging line between its shank and heel portions adjacent the cutters, whereby actuation of the cutters is adapted to make incisions in the surface of the sole extending inward from the edges, and a marking tool between the cutters adapted to produce an indented line on the sole between the incisions. 50
15. A sole-cutting and marking machine comprising a support for a sole, separated cutters having knife edges in alinement, and a non-penetrating indenting tool between and in alinement with the cutters, and provisions for positioning a sole with its length transverse to the line of the knife edges and its edges at the merging line between its shank and heel portions adjacent the cutters, whereby actuation of the cutters is adapted to make incisions in the surface of the sole extending inward from the edges and an indented line extending across the sole between the incisions. 55
16. A sole-cutting and marking machine comprising a base having provisions for supporting a sole, a vibratory tool-carrying head, means for moving the same toward and from the supporting base, and sole-cutting tools separated to act on soles supported by the base adjacent their opposite edges, said tools being laterally adjustable for soles of differing widths, and adjustable in the direction of their operative movement to vary the depth of incisions made thereby. 60
17. A sole-cutting and marking machine comprising a base having provisions for supporting a sole, a vibratory tool-carrying head, means for moving the same toward and from the supporting base, tool holders pivotally mounted on the head and adjustable laterally, and cutting tools carried by said holders. 65
18. A sole-cutting and marking machine comprising a base having provisions for supporting a sole, a vibratory tool-carrying head, means for moving the same toward and from the supporting base, tool holders mounted on the head and adjustable laterally, cutting tools carried by said holders, and cam means for adjusting the holders simultaneously toward and from each other. 70
19. A machine for cutting and marking soles comprising a base adapted to support soles, a cutter head, separated knives carried thereby and movable toward and from the base, and laterally movable gages above the base adapted to embrace a sole lying on said base and hold its edges in line with the knives. 75
20. A machine for cutting and marking soles comprising a base having a flat upper surface adapted to support soles, a cutter head, separated knives carried thereby and movable toward and from the base, side 80

- gages mounted on the support extending above the upper surface thereof, and means for moving them together to engage opposite edges of a sole.
- 5 21. A machine for cutting the lips of a channeled sole, and marking the sole between the cuts, comprising a base adapted to support soles, a cutter head, separated knives carried thereby and movable toward and 10 from the support, a marker between the knives, an end gage, and means for shifting the relative positions of the gage and cutter head longitudinally to vary the location on the sole of the cuts and marks.
- 15 22. The combination of a support for soles, cutting knives normally separated and adjustable toward and from each other, a marker between the knives, end and side gages for positioning the soles with respect 20 to the knives on the support, and means having indexes for adjusting the knives and gages, the knives and marker being movable toward the support to cut and mark soles.
23. A machine for operating on insoles, 25 having in combination a reciprocating cross head, sole slitting knives adjustable thereon for operation on soles of different sizes adapted to cut transverse slits extending part way only through the sole at the points 30 where the stitch receiving rib begins and ends, a support for the sole, and gaging means to determine the position of the sole with relation to the knives.
24. A machine for operating on insoles, 35 having in combination sole slitting knives adapted to cut transverse slits extending part way only through the sole at the points where the stitch receiving rib begins and ends, means for marking the ribbed surface of the sole at predetermined points 40 with relation to said slits to provide a guide for the operator during the inseam sewing and welt butting operations, and gaging and supporting means for the sole.
25. A machine for operating on insoles, 45 having in combination a reciprocating cross head, slitting knives thereon adapted to cut transverse slits extending part way only through the sole at the points where the stitch receiving rib begins and ends, a work 50 support, a presser foot provided with a marking device to mark the ribbed surface of the sole, and gaging means to determine the position of the sole.

In testimony whereof I have affixed my 55 signature, in presence of two witnesses.

MILLER COOK, JUNIOR.
